No. 752,076.

PATENTED FEB. 16, 1904.

O. C. KAVLE.
PAPER GUIDE FOR TYPE WRITERS.

APPLICATION FILED JAN. 31, 1902.

NO MODEL.

UNITED STATES PATENT OFFICE.

OSCAR CARL KAVLE, OF HARTFORD, CONNECTICUT, ASSIGNOR, BY MESNE ASSIGNMENTS, TO UNDERWOOD TYPEWRITER COMPANY, OF NEW YORK, N. Y., A CORPORATION OF NEW JERSEY.

PAPER-GUIDE FOR TYPE-WRITERS.

SPECIFICATION forming part of Letters Patent No. 752,076, dated February 16, 1904.

Application filed January 31, 1902. Serial No. 91,992. (No model.)

To all whom it may concern:

Be it known that I, OSCAR CARL KAVLE, a citizen of the United States, and a resident of Hartford, in the county of Hartford and State 5 of Connecticut, have invented certain new and useful Improvements in Paper-Guides for Type-Writers, of which the following is a full, clear, and exact description.

My invention relates to type-writing machines, and has particular reference to paper-guides, such as are used in connection with the platen to hold the paper firmly against the platen.

The object of the invention is to provide a 15 simple mechanism of the above-indicated class in which a single operating element or shaft is employed for governing the action of two sets of pressure-rollers and in which provision is made for a ready adjustment of the 20 pressure with which said rollers bear against the platen and for a quick and positive release of the paper from said rollers when desired.

My invention consists of the novel construction and arrangement of parts, which will be 25 specifically pointed out in the appended claims.

An example showing how my invention may be carried out in practice is illustrated by the accompanying drawings, in which—

Figure 1 is a bottom plan view of a type-writer platen and the adjacent parts, together 30 with the pressure-rollers and the mechanism connected therewith. Fig. 2 is a sectional elevation on line 2 2 of Fig. 1, and Figs. 3 and 4 are detail views drawn upon an enlarged scale and showing the pressure-rollers 35 in two different positions.

A designates the type-writer platen journaled in a frame, parts of which are indicated by the letter B. In this frame is supported 40 a rod C, extending parallel with the platen, and upon this rod are pivotally carried arms D, the inner ends of which are provided with hubs D', mounted on the said rod C. The outer ends of the arms D are recessed or socketed 45 to receive rods E, upon which are mounted the pressure-rollers F, each of these rollers being preferably independent of the others so

far as rotary motion is concerned. The hubs D' are provided with arms or tappets D², and, as shown in the drawings, there are provided 50 two sets of arms D, the tappets D² of which are arranged out of line transversely. On the rod C are further supported bearings G, held in place by screws G', and in which is journaled a rod or shaft H. This shaft is provided with a milled head H' and is held against longitudinal movement by means of a pin or screw H², engaging a slot in one of the bearings G. The rod or shaft H is provided adjacent to the tappets D² with operating portions H³, which, as shown, are formed by flattening or recessing the shaft at those points. 55

Adjacent to the hubs D', I secure upon the rod C two supporting-collars I, held in place by means of set-screws I' and formed with an 60 eccentric surface relatively to the rod C, as shown in Fig. 4. Upon this eccentric surface is secured a spring J, the free end of which engages one of the arms D, so as to constantly press the same toward the platen and so as to 65 also press the adjacent tappets D² toward each other and into firm engagement with the shaft H. It will be understood that when this shaft is in such a position as to allow the tappets D² to enter the recesses H³ the pressure-rollers F 70 will be in contact with the platen A or with the paper thereon. When, however, the shaft is turned into the position shown in Fig. 3, so that the full thickness or diameter of the 75 shaft will be between the two tappets D², the rollers F will be raised off the platen, and it will then be easy to insert several sheets of paper.

The hubs or collars I perform three functions: 80

First. They serve as supports for the springs J.

Second. They serve as means for adjusting the force with which the springs bear on the arms D. It will be understood that by turning the hubs I on the shaft the action of the spring may be varied, particularly owing to the eccentric formation of the surface to which the spring is attached; but it will be under- 90

stood that even without this formation a turning of the hub I would vary the tension of the spring.

Third. The two hubs I at the same portion 5 of the shaft H serve as a means of confining the adjacent collars D' and for preventing their longitudinal movement. These collars overlap slightly and form shoulders which abut against each other in case one of the rods 10 carrying the pressure-rollers should accidentally, as by a blow, be forced outward beyond the point to which it is brought by the action of the shaft H. By this construction any excessive outward movement of the pressure- 15 rollers is prevented.

The two sets of rollers may be of different diameter, if desired, the smaller ones being located near the discharge-point of the platen adjacent to the customarily-fixed guide K, 20 which may be supported by spring-brackets K', secured to the rod C. The shaft H is also journaled in the central bracket L, which is secured to the rod C and carries a roller M, adapted to travel on the carriage-track accord- 25 ing to a well-known construction of type-writers.

While I have shown and described the details of a specific embodiment of my invention, I desire it to be clearly understood that 30 this is to be taken only as an example of the many forms in which my invention may be carried out.

Now what I claim for my invention, and desire to secure by Letters Patent, is—

- 35 1. The combination with the platen, of a stationary rod located adjacent thereto, arms pivoted on said rod and extending in opposite directions, collars secured adjustably to said rod at each side of the arms, springs extend- 40 ing from the collars and engaging the arms and an operating-shaft arranged adjacent to the arms, the said shaft having irregular portions engaging members projected from the arms to govern the position thereof.
- 45 2. The combination with the platen, of a rod secured adjacent thereto, pivoted arms

extending in opposite directions from said rod, collars adjustably secured to the rod on each side of the said arms and provided with eccentric surfaces, springs secured to the said eccentric surfaces of the collars and engaging the arms, and pressure-exerting devices carried by the arms.

3. The combination with the platen, of a support adjacent thereto, an arm pivoted upon 55 said support, a pressure-exerting device carried by said arm, and a normally stationary spring having a sliding engagement with said arm and secured to said support adjustably so that it may be turned on said support. 60

4. The combination with the platen, of a support adjacent thereto, an arm pivoted on said support, a pressure-exerting device carried by said arm, a collar normally stationary 65 relatively to the support, but capable of being turned thereon for adjustment, said collar being provided with a surface eccentric to the support, and a spring secured to the collar and engaging the arm and the eccentric surface of the collar.

5. The combination with the platen, of a support adjacent thereto, an arm pivoted on said support, a pressure-exerting device carried by said arm, a collar eccentrically mounted to turn on the support for adjustment, 75 means for locking the collar to the support and a spring secured to the adjustable collar and engaging the arm.

6. The combination with the platen, of pressure-exerting devices, tension devices for 80 pressing said pressure-exerting devices toward the platen and independent eccentrically-mounted collars for adjusting the tension devices belonging to different pressure-exerting devices.

In testimony whereof I have signed my name to this specification in the presence of two subscribing witnesses.

OSCAR CARL KAVLE.
